FLUID PRESSURE REGULATOR

Wilgot J. Jacobsson, Plainfield, N. J., assignor to
The Linde Air Products Company, a corporation
of Ohio

Application July 23, 1947, Serial No. 140,465

Term of patent 14 years

(Cl. D52—1)

To all whom it may concern:

Be it known that I, Wilgot J. Jacobsson, a citizen of the United States, residing at Plainfield, in the county of Union and State of New Jersey, have invented a new, original, and ornamental Design for a Fluid Pressure Regulator, of which the following is a specification, reference being had to the accompanying drawing, forming a part thereof.

In the drawing,

Fig. 1 is a side elevational view of a fluid pressure regulator, embodying my new design;

Fig. 2 is a left end view of the device shown in Fig. 1;

Fig. 3 is a right end view of the device shown in Fig. 1; and

Fig. 4 is a top plan view of the device shown in Fig. 1.

The dominant features of my design reside in the portions shown in full lines.

I claim:

The ornamental design for a fluid pressure regulator, as shown and described.

WILGOT J. JACOBSSON.
